UNITED STATES PATENT OFFICE.

GABRIEL ADAM REICHERT, OF CHICAGO, ILLINOIS, ASSIGNOR TO THE AMERICAN MULTIGRAPH COMPANY, OF CLEVELAND, OHIO, A CORPORATION OF OHIO.

ADJUSTABLE SUPPORTING DEVICE FOR TYPE-HOLDING SEGMENTS.

1,275,472.

Specification of Letters Patent. Patented Aug. 13, 1918.

Application filed May 5, 1917. Serial No. 166,627.

To all whom it may concern:

Be it known that I, GABRIEL ADAM REICHERT, a citizen of the United States, residing at Chicago, in the county of Cook and State of Illinois, have invented a certain new and useful Improvement in Adjustable Supporting Devices for Type-Holding Segments, of which the following is a full, clear, and exact description, reference being had to the accompanying drawings.

The object of this invention is to provide a cheap and simple stand for holding removable segments of printing machines while type is being loaded on the segment or removed therefrom. My invention is particularly well adapted for loading the removable segment of the multigraph during its loading or unloading by means of suitable hand tools. The multigraph segment, as shown, for example, in Patent No. 1,122,728, is a semi-cylindrical member having transverse stiffening ribs on its concave side and on its convex side having longitudinal rails with overhanging edges, thus providing undercut channels into which grooved type may be shoved longitudinally. A convenient loading and unloading tool to coöperate with such segment is shown in Patent No. 955,534, and comprises a tube slotted parallel with its axis and having projections at its ends adapted to enter two of the drum channels on opposite sides of the channel with which the slot aligns.

When transferring type to or from the multigraph segment from a holder, such as the slotted tube described, it is very desirable to have the particular line being transferred near the top of the segment. In other words, it is most convenient to have the segment tipped up when loading or unloading of channels in the vicinity of its edges. My stand provides for this in a very simple and effective way.

My stand comprises a base, a standard swiveled thereto to turn on a vertical axis and an arc-shaped support for the segment, hinged to the standard on a horizontal axis. Means are provided for clamping the arcual support in any desired position on the standard, whereby any channel of the segment may be held in the most accessible position for loading and unloading.

My invention is hereinafter more fully

described in connection with the accompanying drawings, and its essential characteristics are summarized in the claims. 55

In the drawings, Figure 1 is a perspective view of my device in use holding a multigraph segment which is being loaded or unloaded by the use of a temporary holding tube and a suitable shoving tool; Fig. 2 is a vertical section through my supporting device, the multigraph segment being indicated in place in broken lines; Fig. 3 is a sectional side elevation of my supporting device at 60 right angles to Fig. 2; Fig. 4 is a side elevation of a portion of my supporting device adjacent to the horizontal hinge between the arcual support and the standard. 65

As shown in the drawings, 1 indicates the base of my supporting device, which is preferably an inverted saucer-shaped casting. Swiveled centrally to this base is the standard 2, the standard having a reduced extension 3 extending through the base and being 70 provided with a suitable holding device, as, for example, a cotter pin 4, within the recess which is beneath the base. The standard 2 is bifurcated, as shown at 5, to provide for the hinge engagement with the arcual member which carries the segment. 75

The arcual supporting member is designated 6 and is preferably a single integral casting having an arcual portion, which may be reduced in weight by recesses 7 on its opposite sides, and having a radial tongue 8 which is hinged to the standard. This tongue has a reduced flattened portion 9, which extends into the recess 5 of the bifurcated standard. A bolt 10 passes through 80 the standard and the extension 9 of the arcual member, and carries a nut 11. 85

The construction described hinges the arcual member to the standard. It provides also for clamping the arcual member in any desired position. For the convenient effecting of this the nut 11 is preferably a wing nut and the bolt is preferably stationary in the standard. I have shown for this purpose a carriage-bolt having its squared portion 95 engaging a corresponding hole in one of the standard sides. 100

To limit the swing of the arcual member in either direction I provide wings 12 on the standard which may be engaged by the 105 abrupt shoulder 13 formed where the re-

duced portion of the tongue 9 leaves the main portion 8. This is clearly illustrated in Fig. 4.

A multigraph segment is shown at A in Fig. 1, a type-holding transfer tube at B, and a suitable pointed instrument for shifting the type at C. The segment is provided at its exterior with parallel longitudinal overhanging rails a and has transverse stiffening webs a' . As usually constructed the segment has four of these webs, as shown in Fig. 2. The segment is also provided with a longitudinal rod a^2 carried by those webs, which supports hooked leaf springs a^3 located between the outermost webs and those adjacent to them, these springs coacting with the multigraph drum to hold the segment in place. My holding device is designed to engage the segment between the two intermediate webs. The thickness of the arcual head is of such dimension that it may readily enter the space between these webs. This head is also provided with a central notch 14 in its outer portion, adapted to be occupied by the rod a^2 , which prevents the segment shifting circumferentially on the head.

It will be seen that the multigraph segment may be placed on my device without making any change whatever in the segment. By reason of the swiveling of the standard, the segment may be turned around to present the free end in the most available position for loading or unloading. Then, by swinging the support on the horizontal pivot, the segment may be tipped to bring any channel into convenient loading or unloading position. The stopping wings 12 on the standard and the coacting shoulder 13 are so located that in either extreme position the segment still remains in position by gravity. Accordingly, there is no danger of it tipping off. By tightening the thumb nut 11 properly with the fingers sufficient friction may be obtained between the standard and the arcual member to hold the segment in any desired position, and at the same time allow it to be swung to bring a new channel into this position. It is accordingly not necessary to change the clamping nut with each shifting of the segment.

Having thus described my invention, what I claim is:

1. In a device of the character described, the combination of a base, a standard carried thereby, a head adapted to support a type engaging segment, said head being provided with a downwardly extending centrally located tongue, and means pivoting the tongue to the standard.

2. The combination of a base, a standard swiveled thereto, a head formed to support a segment and having a tongue hinged to the standard, and means for holding the

head with its tongue at various angles to the standard.

3. In a device of the character described, the combination of a base and an arcual supporting device adapted to engage and support a type holding segment, said device being swiveled to the base on a vertical axis.

4. In a device of the character described, the combination of a base, a standard swiveled thereto, and a member adapted to support a segment hinged to the standard.

5. The combination with a base, of a member having a curved top and adapted to support a type-holding segment, a standard swiveled to the base, and means for adjustably clamping the curved member to the standard.

6. The combination of a base, a standard rotatably connected therewith on a vertical axis, a member having a curved top and a radial tongue pivotally connected with the standard, and shoulders limiting the movement of said member in either direction.

7. The combination of a base, a standard swiveled thereto, a head adapted to support a type-holding segment and having a downwardly extending tongue, a bolt and nut pivoting the tongue to the standard and furnishing means for clamping the head in desired position.

8. The combination, with a segment having transverse webs on its concave side, of a device having a pivotally mounted supporting member adapted to engage the segment between the webs, means for clamping the device in various adjusted positions.

9. The combination, with a type-holding segment having transverse webs on its concave side, of a stand to support the same having a head curved concentrically of the segment and adapted to stand between adjacent webs and engage the inner surface of the segment, a base having a standard rising from it, and a pivoted connection between the standard and said head.

10. The combination, with a segment having webs on its concave side, of a swiveled and jointed supporting device adapted to engage the segment between webs.

11. The combination with a segment having webs on its concave side, of a support adapted to engage the segment between webs, a standard to which the support is hinged, stops limiting the swinging of the support and a base to which the standard is swiveled.

12. The combination, with a segment having webs on its concave side, of a swiveled and hinged support adapted to engage the segment between webs, and means for preventing the segment shifting on the support.

13. The combination, with a segment having webs on its concave side, of a swiveled

and hinged support adapted to engage the segment between webs, and a notch in the upper surface of the segment adapted to be occupied by a rod on the segment.

5 14. The combination, with a segment adapted to hold type, of a supporting stand therefor having a base, a member engaging the segment, and means connecting said member with the base and allowing the

member to swing on both vertical and horizontal axes, means for limiting the movement of the device on the horizontal axis, and means for preventing the segment shifting on the member. 10

In testimony whereof, I hereunto affix my 15
signature.

GABRIEL ADAM REICHERT.
